UNITED STATES PATENT OFFICE.

CLARK J. SMITH, OF OTTUMWA, IOWA, ASSIGNOR TO THE HARDSCOG
WONDER DRILL CO., OF OTTUMWA, IOWA.

ROCK-DRILL.

No. 837,347.

Specification of Letters Patent.

Patented Dec. 4, 1906.

Application filed July 5, 1906. Serial No. 324,804.

To all whom it may concern:

Be it known that I, CLARK J. SMITH, residing at Ottumwa, in the county of Wapello and State of Iowa, have invented certain new and useful Improvements in Rock-Drills, of which the following is a specification.

My invention relates to certain new and useful improvements in rock-drills in which means are provided for washing or blowing out the chips and dust from the apertures being drilled.

Generically my invention comprises a rock-drilling machine having means adjacent the lower or drill-receiving end whereby water, either uncompressed or compressed, may be fed or forced into the hole being drilled either alone or in a mixture with the exhaust working agent used to operate the drilling engine or hammer—viz., steam or compressed air.

My invention also includes means whereby the action of the exhaust working agent may be cut out entirely without cutting out the water-supply to the hole and means whereby the water-supply may be cut out while the exhaust working agent alone is used to blow out the debris from the hole being drilled. Also means are provided for so regulating the water and air supply to the drill that any desired proportionate mixture of the two can be forced through the drill at will.

In its more subordinate nature my invention comprises a drilling-engine and casing therefor, whose drill-receiving end is provided with a chuck and a series of radial apertures in communication with a central passage of the hammer-barrel of the casing, a swivel-ring mounted on the hammer-barrel over the radial apertures to which the valved water-supply pipe connects, and a valved impact-receiving member within the chuck end of the hammer-barrel and forming a valved passage from the exhaust-chamber of the drilling-engine to the drill-tool. The exhaust-chamber also has a valved exhaust-port by means of which the exhaust can be made to pass directly to the atmosphere or through the impact-receiving member into the drill.

With other objects in view than have been heretofore specified the invention also includes certain novel construction, combination, and arrangement of parts, all of which will be first described in detail and then be

specifically pointed out in the appended claims, reference being had to the accompanying drawings, in which—

Figure 1 is a perspective view showing my invention applied for use, the rock at the drill being shown in section to more clearly illustrate the invention. Fig. 2 is a vertical longitudinal section of the drilling-engine mechanism. Fig. 3 is an enlarged section of a portion thereof. Fig. 4 is a cross-section on the line 4-4 of Fig. 3. Fig. 5 is a detail perspective view of the impact-receiving member with its parts separated. Figs. 6 and 7 are detail views of the drill-tool.

In the accompanying drawings, in which like characters of reference indicate like parts in all of the figures, I have illustrated my present invention as applied to a drill of the type shown in my Patent No. 812,375, of February 13, 1906, although I do not desire it understood that the present invention is limited in use to the drilling mechanism referred to, as it may be adapted to any other drilling mechanism of the reciprocating-hammer type.

1 designates the drill-casing, which is externally threaded at 1^a and has an internal bore 1^b to receive the hammer-barrel 2, which is tightly fitted thereon, with its front portion projecting beyond the front edge of the drill-casing, which is provided with a central threaded bore 1^c to receive the plug 3, which has a central hollow chamber 3^a and a flange 3^b, which abuts the end of the casing or barrel 1 of the drill. The plug 3 also has a laterally-extending portion 3^c, provided with an externally-threaded portion 3^d and whose end 3^e is adapted to receive the crank or handle 4, which is secured thereto, as shown. The plug 3 has a plurality of radial apertures 3^f, which communicate with the chamber 3^a and with the outside of the plug 3.

Fitted on the extension or hub portion 3^e of the plug 3 is a loose collar 5, which has a central internal chamber 5^a to cooperate with the apertures 3^f and an externally-threaded pipe 5^b to receive the pipe connections 6 of the air-supply pipe 7. The pipe 7 is controlled by the valve 7^a. On each side of the loose collar 5 is a fiber or rubber washer 8, that is placed on the hub of the extension 3^e of the plug 3. The washers 8 and the collar 5 are held in position by the check-nuts 9, threaded on the portion 3^d of the plug 3, it

being understood that the collar 5 is adjusted to permit the barrel 2 and the plug 3 being rotated without rotating the collar 5.

The hammer-barrel has a chamber 2^a to receive the drill-chuck 10, in which the drill 11 is held, and the chuck 10 abuts the internal web 2^b of the barrel 2, which barrel 2 is also provided with internal webs 2^c and 2^d and annular chambers 2^e, 2^f, 2^g, and 2^h, respectively. The rear end 2^m of the barrel is internally threaded at 2ⁿ to receive the plug 12. Ports 2^r, which communicate with the rear portion 1^x of the chamber 1^b of the casing 1, are formed in the barrel 2 and communicate with the interior of the barrel to the ports 2^t. Within the barrel 2 the hammer-piston 13 reciprocates, and this piston has the usual head 14 and an enlarged annular portion 13^a at the rear thereof, while a chamber 13^b is formed within the piston 13 and is opened at the rear of the piston to communicate with the chambers 2^g and 2^h of the barrel 2, a series of radial ports 13^c being also provided for the same purpose, while a series of ports 13^d are arranged adjacent the head 14 and open up communication between the chamber 13^b and the chamber 2^e when the piston is at the final limit of its stroke and permit the exhaust to pass from the chambers 2^g 2^h into the chamber 2^e, which I shall herein-after term the "exhaust-receiving chamber," while the piston 13 communicates with the chamber 2^g when the piston is at the rear portion of its stroke to permit the working charge to enter into the chamber 13^a and the chambers 2^g and 2^h to force the piston again forward.

As before stated, the barrel 2 projects from the web 2^c beyond the end of the barrel-casing 1 and is provided with a shoulder 20 and a threaded portion 21, as indicated. The drill-holding end of the barrel has a supplemental bore 22 to receive the impact-receiving member 23, hereinafter again referred to.

24 designates a collar mounted on the outer end of the barrel 2, and the collar 24 is held in place to permit free rotation of the barrel 2 by rubber washers 26 and check-nuts 26^a on the threaded portion 21 of the barrel. The collar 24 has an internal groove or chamber 24^a to communicate with the aperture 2^x of the barrel 2, which aperture in turn connects with the outer annular groove 23^x in the impact-receiving member 23. The collar 24 has a tap 24^b to receive the water-supply pipe 25, which has a control-valve 25^a, by means of which the water-supply to the drill 11 can be regulated. The drill 11 has a central passage 11^a run from end to end to conduct the water into the hole.

In order to prevent the water being forced into the exhaust-chamber when water under pressure is used, I provide the member 23 with a back check-valve 23^b, which may be held lightly seated by a coil-spring 23^a, as

shown. The exhaust-port 2^x of the barrel 2 is preferably provided with a control-valve 2^v, whereby the entire exhaust charge (when the valve 2^v is closed) may be forced through the check-valve 23 and through the drill out of the hole, or the entire exhaust charge may pass out of the valve 2^v when fully open. By opening the valve 2^v to a greater or less degree a varying amount of the exhaust charge will pass through the check-valve 23^b and the drill to the hole to aid in expelling the debris.

In carrying out my invention the drill is fed to the hole by manipulating the crank 4, and when the valve 7^a is open to permit the working agent to pass (compressed air or steam) into the casing 1 it operates the hammer-piston 13 in a manner which will be clearly understood by reference to the drawings and to my patent hereinbefore referred to. I have found by experiment that water may be sent into the drill under pressure and the exhaust from the drill may be also passed through with the water, thus getting very good results. The drill, however, will operate very well either with the water alone or with the exhaust alone being forced into the drill, although I prefer to combine them. When it is desired to use a mixture of exhaust working agent, (which, it should be understood, is still slightly under pressure,) I open the valve of the pipe 25 to admit the water and close off the exhaust-valve of the exhaust-port from the chamber 2^e, thus compelling such exhaust to join the water and pass through the drill with it into the hole to allay the dust and force out the debris.

By properly adjusting the water-inlet valve and the exhaust-port valve I can cause the drill-operating working-agent exhaust and the water to so coact as to form, as it were, a sprayer and force the water into the hole through the drill as a spray and without materially interfering with the quick and effective exhaust charge from the chamber 2^e, it being understood that the exhaust-port valve may be opened to atmosphere sufficiently to prevent the pressure in the exhaust-chamber accumulating to such an extent as to effect the efficient operation of the hammer.

From the foregoing description, taken in connection with the accompanying drawings, it will be seen that I have provided a very simple and effective construction of drilling mechanism in which means are provided which will readily and effectively serve their intended purposes and that by mounting the member 23 in the barrel, as shown, it will be held in place and its movement limited by the drill-chuck 10 and the shoulder 2^x of the barrel 2. Again, it is thought from the foregoing description, taken in connection with the accompanying drawings, the complete construction, operation, and numerous ad-

vantages of my invention will be readily understood by those skilled in the art to which the invention appertains, and I desire to say that many slight changes in the detail construction, arrangement, and design of parts may be readily made without departing from the scope of the invention or that of the appended claims.

What I claim is—

10 1. In a rock-drill, the combination with the hammer-barrel and the hammer, said barrel having an inlet and an exhaust chamber, of a drill having a longitudinal passage therethrough and held in one end of said hammer-barrel, said barrel having a water-chamber, means for admitting water into said water-chamber to pass through said drill, said hammer-barrel having a valved passage between the exhaust and the water 15 chambers, and means for controlling the water admission to the water-chamber, substantially as shown and described.

2. In a rock-drill, the combination with the hammer-barrel and the hammer, said barrel having an inlet and an exhaust chamber, of a drill having a longitudinal passage therethrough and held in one end of said hammer-barrel, said barrel having a water-chamber, means for admitting water into 25 said water-chamber to pass through said drill, said hammer-barrel having a valved passage between the exhaust and the water chambers, means for controlling the water admission to the water-chamber, said barrel having an exhaust-port from said exhaust-chamber to the atmosphere.

3. In a rock-drill, the combination with the hammer-barrel and the hammer, said barrel having an inlet and an exhaust chamber, of a drill having a longitudinal passage therethrough and held in one end of said hammer-barrel, said barrel having a water-chamber, means for admitting water into 40 said water-chamber to pass through the drill, said hammer-barrel having a valved passage between the exhaust and the water chambers, means for controlling the water admission to the water-chamber, said barrel having an exhaust-port from said exhaust-chamber to the atmosphere, and means for controlling the exhaust-through said exhaust-port.

4. In a drill, the combination with a hammer-barrel, and a hammer mounted therein, a drill-chuck held in one end of said barrel, and 45 a longitudinally-apertured drill held in said drill-chuck, said barrel having an exhaust-chamber, said barrel having a water-receiving chamber, an impact-receiving member held in said water-chamber and projecting into the exhaust-receiving chamber, said impact-receiving member having a passage communicating with the exhaust-receiving chamber and the water-receiving chamber, means for admitting water into said water-chamber, said barrel having an exhaust-port 50

communicating between the exhaust-chamber and the atmosphere, substantially as shown and described.

5. In a drill, the combination with a casing, a drilling-engine within the casing, a drill-chuck in one end of said casing, said casing having an exhaust-receiving chamber and a water-receiving chamber, an impact-receiving member held in said water-receiving chamber and projecting into the exhaust-receiving chamber, said impact-receiving member having a passage therethrough communicating with the water and with the exhaust receiving chambers, a collar or ring mounted on said casing, said ring having an internal annular chamber, radial ports in said casing to open up communication between said internal annular chamber and the water-chamber of the casing, means for passing water through said annular ring to its annular chamber.

6. In a drill, the combination with a casing, a drilling-engine within the casing, a drill-chuck in one end of said casing, said casing having an exhaust-receiving chamber and a water-receiving chamber, an impact-receiving member held in said water-receiving chamber and projecting into the exhaust-receiving chamber, said impact-receiving member having a passage therethrough communicating with the water and with the exhaust receiving chambers, a collar or ring mounted on said casing, said ring having an internal annular chamber, radial ports in said casing to open up communication between said internal annular chamber and the water-chamber of the casing, means for passing water through said annular ring to its annular chamber, and said drill-casing having an exhaust-port to communicate between the exhaust-receiving chamber and the atmosphere.

7. In a drill, the combination with a casing, a drilling-engine within the casing, a drill-chuck in one end of said casing, said casing having an exhaust-receiving chamber and a water-receiving chamber, an impact-receiving member held in said water-receiving chamber and projecting into the exhaust-receiving chamber, said impact-receiving member having a passage therethrough communicating with the water and with the exhaust receiving chambers, a collar or ring mounted on said casing, said ring having an internal annular chamber, radial ports in said casing to open up communication between said internal annular chamber and the water-chamber of the casing, means for passing water through said annular ring to its annular chamber, said drill-casing having an exhaust-port to communicate between the exhaust-receiving chamber and the atmosphere, and said impact-receiving member having a check-valve, substantially as shown and described.

8. In a rock-drill, the combination with a drill-casing having a water-receiving chamber and an exhaust-receiving chamber, of a valved impact-receiving member held in said 5 drill-chamber and having communication with the exhaust-receiving chamber, means for admitting water into the water-receiving chamber, said drill having an exhaust-port communicating between the said receiving- 10 chamber and the atmosphere, means for controlling the exhaust-port, and means for controlling the water admission to the water-receiving chamber.
9. The combination with a drill-casing, a 15 piston reciprocating therein, said casing having an exhaust-receiving chamber near one end, a water-receiving chamber in the same end adjacent the exhaust-receiving chamber, a drill-chuck held in the casing, and communicating with the water-receiving chamber, an impact-receiving member held in the water-receiving chamber and projecting into the exhaust-receiving chamber and having a 20 passage in communication with both chambers, said impact-receiving member having an external annular groove and radial apertures connecting said groove with the internal passage of the impact-receiving member; said drill-casing having radial apertures 25 communicating with the water-chamber and the exterior of the casing, and an annular inter-
- nally-chambered ring held on said casing over said radial apertures, packing-rings held on either side of said annular ring, check-nuts for securing said annular ring and packing 30 members in position, a valved water-supply pipe connected with said annular ring and in communication with the internal chamber thereof, said drill-casing having an exhaust-port, all being arranged substantially as 35 shown and described.
10. The combination with a drilling-engine, a drill-chuck carried thereby, a hollow drill held in said chuck, said drilling-engine having a water-chamber and an exhaust- 40 receiving chamber, means provided with a communication between said chambers, means for supplying water to the water-chamber, said exhaust-receiving chamber having an exhaust-port communicating with 45 the atmosphere and means for controlling the outlet of the exhaust through the exhaust-port, and means for controlling the inlet of the water to the water-chamber to enable the proportionate feed of water and 50 exhaust through the drill to be regulated, substantially as shown and described.

CLARK J. SMITH.
